UNITED STATES PATENT OFFICE.

PETER G. SCHMIDT, OF OLYMPIA, WASHINGTON.

GAS-PRODUCER.

1,116,131.

Specification of Letters Patent.

Patented Nov. 3, 1914.

Application filed March 26, 1913. Serial No. 757,020.

To all whom it may concern:

Be it known that I, PETER G. SCHMIDT, a citizen of the United States, residing at Olympia, in the county of Thurston and State of Washington, have invented a new and useful Gas-Producer, of which the following is a specification.

This invention relates to improvements in gas producers, and more especially to that type of producers known as rotary gas producers, the main object of the present invention being the provision of a means whereby rotary gas producers will generate and deliver from fuel having high volatile content, a much cleaner gas than is generally produced by this type of producer at the present state of the art, thereby increasing the thermal efficiency of the producer, making the cleaning of the gas much easier and also eliminating the necessity of disposing of large quantities of tar and other condensates from the gas.

The present invention in one form is applicable to the usual type of updraft rotary gas producer which has previously been provided with a centrally disposed depending gas collector, the present gas producer being designed to deliver a very much cleaner gas, causing less trouble from pipe and flue stoppage and consequently frequent shutdowns for cleaning; and this also economizes in the apparatus, power and water for gas washing purposes in addition to giving the producer a high thermal efficiency.

A still further object of the present invention is the provision of means whereby the usual form of rotary gas producer has its field of operation and usefulness increased for especially the use of soft coals and for the purpose where the use of clean or washed gas is mandatory in contra-distinction to gas or "smoke-gas" application, to which application the existing modes of producers are practically limited when using fuel of considerable volatile content.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a vertical

central sectional view of a rotary producer equipped with the present invention. Fig. 2 is an enlarged detail sectional view of a mechanically tight lubricated sliding joint between the stationary and moving members of the air supplying means of the producer.

Referring to the drawings, the numeral 1 designates the base or supporting structure which is provided with the ash reservoir 2 through which the ash is adapted to be removed from the present producer. An air conducting flue 3 is provided upon the base and communicates with the twyer or distributing chamber 5, the same being provided with the flattened conical top 6, which is disposed in spaced relation to the upper edge of the chamber 5 so that air will be distributed to the circumferential space into the ash zone and the lower part of the fuel bed. This section 7 is provided with the outstanding rim 8, which carries the water sealed receptacle 9 and is supported upon rollers 11 carried by the supporting posts 12-12'. By this means the section 7 is permitted to be rotated relatively to the base 1. Peripheral teeth 13 are provided upon the outer surface of the water sealed chamber 9 and mesh with the small gear 15 upon the vertical shaft 14, said shaft 14 being also provided with the large gear 16, said shaft constituting a means whereby the section 7, and upper section 17, as will presently appear, are rotated. The upper section 17 is provided with the outwardly projecting flange and supporting rim 18, which is disposed to rest upon a plurality of rollers 19 supported upon the posts 12 and 12', and thus provide an upper support for the section 17, which is provided with the annular water chamber 20, which with the apron 21 of the water cooled top or charging floor 22, provides a water seal between the two, so that as the top 22 is rigidly and stationarily supported through the inturned ends 23 and 23' of the supports 12 and 12', the section 17 may be properly rotated. The flange 18 is provided with gear teeth 24, which mesh with the gear 16, so that the upper section may be rotated.

One or more coal or fuel inlets and hoppers 30' are provided, while the gas outlet 35' from the collector 33 is also provided. The usual poke holes 31, which are held tight by means of the lids or covers 32 are also provided.

It is desirable that an auxiliary current

of air be supplied through the body of the fuel between the upper surface thereof, to assist in the gasification of the distillate contained therein. Therefore in the structure 5 shown, humidified air is supplied through the conduit 25 to an annular chamber 26, the depending rims thereof being disposed within the liquid sealed chamber 27, which is connected to and rotatable with the section 10 17 through the vertical conduit 28, the outlets 28' of which are disposed to register with the nozzle 29, disposed within the peripheral openings 29' of the section 17. These openings 29' lead directly into the 15 fuel magazine, so that the tendency of the air drawn therein will follow the direction of the arrows shown in Fig. 1 through the body of fuel into the inner end of the gas collector 33.

20 As shown in Fig. 2, the conduit 25' leads into the annular seating member 26' of the air-distributer, its flanges 26^b, fitting between the upstanding flanges 27^a and 27^b of the producer carried member 27'. The 25 flanges 26^b have their lower edges snugly seated in the member 27', while the spaces adjacent the flanges 27^a and 27^b are to be filled with a lubricant. The pipe 28' leads from the member 27' to the nozzle 29 disposed in the opening 29' in the refractory 30 wall of the producer.

What is claimed is:

1. A gas producer, having a lower air inlet, a centrally depending gas collector, the

wall of the producer above the lower end of 35 the collector being provided with means for conducting auxiliary air thereinto, said means including an annular stationarily mounted member having an extending rim in communication with an air supply, an 40 inverted ring telescopically fitting the same and forming therewith a sealed joint, and conduits leading from the latter to the auxiliary air inlet of the producer.

2. A gas producer, having a revolute fuel 45 chamber section and a lower air inlet, a centrally depending gas collector projected into the fuel body, and means for supplying auxiliary air adjacent the periphery of the producer at a point above the lower end of the 50 gas collector and below the top surface of the fuel body, and consisting of a humidified air conducting pipe, a telescopic water seal consisting of two coaxing members, one fixedly connected to the air conducting pipe 55 and the other connected for rotation with the revolute section, and a plurality of nozzles leading therefrom and through the wall of the section at a point above and in spaced relation to the lower end of the gas collector. 60

In testimony that I claim the foregoing as my own, I have hereto affixed my signature in the presence of two witnesses.

PETER G. SCHMIDT.
